UNITED STATES PATENT OFFICE.

MARY LOYD, OF PHILADELPHIA, PENNSYLVANIA, ASSIGNOR TO LOEB,
LIPPER & CO., OF SAME PLACE.

DESIGN FOR TRIMMING.

SPECIFICATION forming part of Design No. 26,602, dated February 2, 1897.

Application filed December 22, 1896. Serial No. 616,668. Term of patent 7 years.

To all whom it may concern:

Be it known that I, MARY LOYD, a citizen of the United States, residing in the city and county of Philadelphia, State of Pennsylvania, have invented and produced a new and original Design for Trimming, of which the following is a specification, reference being had to the accompanying drawings, forming part thereof.

- o The leading features of my design for trimming are, first, a body of pendants with a head of loops thereon, and, next, a row of double loops surmounting said head.

Figure 1 represents a face view of a piece of trimming embodying my design. Fig 2 represents an end view thereof.

In the drawings, A designates the body of the trimming, and B the head thereof. The body is of the form of looped pendants, and the head is composed of loops projecting from the upper ends of said pendants.

Surmounting the head is a row C of double loops.

What I claim is—

The design for trimming, substantially as shown and described.

MARY LOYD.
